PAN AND UTENSIL WASHER

Robert K. Nolte, Chatham, N.J., assignor to Metalwash
Machinery Company, Elizabeth, N.J., a copartnership

Filed June 8, 1962, Ser. No. 70,480

Term of patent 14 years

(Cl. D49—1)

T19-3.

T19-4.

T19-5.

T19-6.

FIG. 1 is a front elevational view of a pan and utensil washer showing my new design;

FIG. 2 is a front perspective view thereof shown in open position;

FIG. 3 is a front elevational view thereof;

FIG. 4 is a side elevational view thereof;

FIG. 5 is a top plan view thereof; and

FIG. 6 is a side elevational view thereof shown in open position.

The rear and side not shown are plain.

The dominant features of my design reside in the portion shown in full lines.

What I claim is:

The ornamental design for a pan and utensil washer, as shown and described.
